Primary Examiner — John Windmuller*Assistant Examiner* — John R Yeh(74) Attorney, Agent, or Firm — St. Onge Steward Johnston & Reens LLC(57) CLAIM

The ornamental design for a guitar body, as shown and described.

DESCRIPTION

FIG. 1 is the front view for a guitar body in accordance with my new design;

FIG. 2 is a rear view thereof;

FIG. 3 is a top view thereof;

FIG. 4 is a bottom view thereof;

FIG. 5 is a right side view thereof;

FIG. 6 is a left side rear view thereof;

FIG. 7 is a front perspective view thereof;

FIG. 8 is a front perspective view showing my design within an environment thereof; and,

FIG. 9 is a rear perspective view showing my design within an environment thereof.

The broken lines depict environmental subject matter only and form no part of the claimed design.

1 Claim, 4 Drawing Sheets(56)
